UNITED STATES PATENT OFFICE.

WALTER H. SIMONSON, OF NEW YORK, N. Y.

DESIGN FOR A FLAG, BANNER, SIGN, POSTER, PENNANT, BADGE, EMBLEM, PIN, BUTTON, RING-TOP, OR SIMILAR ARTICLE OF MANUFACTURE.

53,166.

Specification for Design.

Patented Apr. 1, 1919.

Application filed January 13, 1919. Serial No. 270,978. Term of patent 3½ years.

To all whom it may concern:

Be it known that I, WALTER H. SIMONSON, a citizen of the United States, residing at New York city, in the county of Kings and State of New York, have invented a new, original, and ornamental Design for a Flag, Banner, Sign, Poster, Pennant, Badge, Emblem, Pin, Button, Ring-Top, or Similar Article of Manufacture, of which the following is a specification, reference being had to the accompanying drawing, forming part thereof.

The figure shows a face view of an emblem, an article of manufacture showing my new design, embodying two angular presentations.

I claim:

The ornamental design for a flag, banner, sign, poster, pennant, badge, emblem, pin, button, ring top, or similar article of manufacture, as shown.

WALTER H. SIMONSON.
